(57) **CLAIM**

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing our new design according to a first embodiment;

FIG. 2 is a front view of a display screen or portion thereof with icon showing our new design according to a second embodiment;

FIG. 3 is a front view of a display screen or portion thereof with icon showing the icon of FIG. 1 in an alternative environment;

FIG. 4 is a front view of a display screen or portion thereof with icon showing the icon of FIG. 1 in an alternative environment;

FIG. 5 is a front view of a display screen or portion thereof with graphical user interface showing the icon of FIG. 1 in a graphical user interface; and,

FIG. 6 is a front view of a display screen or portion thereof with graphical user interface showing the icon of FIG. 1 in a graphical user interface.

The outer perimeter illustrated by a dot-dash broken line in the drawings illustrates a display screen or portion thereof and forms no part of the claimed design. The dashed broken lines in FIG. 4 illustrate a computer monitor that forms no part of the claimed design. The dashed broken lines in FIGS. 5-6 illustrate portions of a graphical user interface that form no part of the claimed design.

1 Claim, 6 Drawing Sheets
(5 of 6 Drawing Sheet(s) Filed in Color)
